UNITED STATES PATENT OFFICE.

GEORGE E. LLOYD, OF CHICAGO, ILLINOIS.

SHAVING-MACHINE FOR CURVED PLATES.

SPECIFICATION forming part of Letters Patent No. 367,987, dated August 9, 1887.

Application filed April 22, 1887. Serial No. 225,753. (No model.)

To all whom it may concern:

Be it known that I, GEORGE E. LLOYD, of Chicago, in the county of Cook and State of Illinois, have invented certain new and useful 5 Improvements in Stereotype Curved-Plate-Shaving Machines; and I do hereby declare that the following is a full, clear, and exact description of the invention, which will enable others skilled in the art to which it appertains 10 to make and use the same, reference being had to the accompanying drawings, and to letters of reference marked thereon, which form a part of this specification.

Heretofore it has been customary when shaving the backs of circular plates, such as are used in revolving type-cylinder presses, to place them in a stationary concave bed, and then by means of a revolving knife, the periphery described by which corresponds to 20 the concavity of the back of said plate and in register therewith, shave the same.

The object of my invention is to reverse this order, believing, as I do, that the operation is more satisfactory and positive in its results, 25 and make the bed revolve around the stationary knife. Besides this, I am enabled by such construction to trim the end edges of the plate at the same time it is being shaved by means which with the old construction it is very difficult to do.

In the drawings, Figure 1 is a perspective view of my invention. Fig. 2 is a transverse vertical section of the same at about its center of length. Fig. 3 is a transverse vertical section near the right-hand end of the machine, as shown in Fig. 1, looking into the bed thereof. Fig. 4 is a transverse vertical section thereof near the left-hand end of the same, looking into the bed.

Reference being had to the drawings, A represents a rectangular frame resting upon and supported by four legs, 1.

B B represent two circular bearing frames, provided with laterally-projecting lugs which 45 rest upon and are secured to the upper flanged edges of the sides of frame A, and C represents an inverted-V frame having secured in its vertex the longitudinal stationary knife-carrying shaft b.

The bed D has its bearings in the bearing frames B B, and revolves around the knife E. It could be made perfectly cylindrical; but I

prefer to make it as shown—viz., the half in which the plate is placed semicircular and the other half cut away, except at its ends, which are left intact, so as to furnish a perfectly circular journal within the bearing frames B. These bearing-frames are located sufficiently far apart so that the end edges of the bed D are flush with the outer edges thereof.

Mounted on shaft b, so that the projecting part thereof, to which knife E is adjustably secured, may be between the end edges of the bed, is the knife-frame c. Shaft b extends slightly beyond the boss of knife-frame c, and 65 rests within the bore of the boss of the wheel-frame d, which serves alike as a support for the adjacent end of shaft b and at the same time as a brace for that end of the bed in which it is inserted.

The back of the knife-frame c is curved like an evolute, while its inner surface, to which the knife is secured and is adjustable radially to and from the work, is flat.

Secured by bolts or otherwise to the circular edges of the end of the bed farthest from the V frame, in which shaft b is secured, is a worm-gear, F'. This worm-gear meshes with and is driven by a worm, G, on the transverse driving-shaft g, suitably journaled in the sides 80 of frame A. On the outer end of this shaft g is a loose pulley, e, which is driven, through the medium of a belt, by the main shaft. As it would not do to have the bed revolving all the time, it is necessary to so control its actuating mechanism—to wit, the driving-shaft—that when the bed D has revolved sufficiently to shave the plate and is in position for the shaved plate to be removed and another inserted it can be stopped or started up at will. This I 90 accomplish by serrating the inner edges of the boss of said pulley and engaging it by a clutch, F, which, by means of a spline on said shaft, can move longitudinally, but not revolve independently of the shaft. This clutch is thrown in and out of engagement with the pulley by means of the bifurcated arm f, projecting from the contiguous end of the transverse reciprocating rod h, the bifurcated arms of which turn inwardly toward the shaft g into the circumferential groove in said clutch F, as shown.

Projecting vertically from the boss of arm f is a pin, which passes through the contiguous end of a hand-lever, I, which is fulcrumed near

said end to a lug projecting laterally from frame A, and pursues a longitudinal course toward the opposite end of the machine, where it can be easily manipulated by the operator.

5 I utilize rod *h* to automatically stop the bed when the work is shaved and in position to be removed. The position the bed should be in when this is the case is substantially that shown in Fig. 1. When the bed is in this position, I secure at a point intersected by a vertical line passing through the center of shaft *b*, to the inner edge of the circular end or journal of the bed, a plate, *h'*, from which an finger, *k*, projects downward so that its vertical portion is on the same vertical plane as said rod *h*. Journaled on a stud projecting laterally from a point on the inner edge of the adjacent bearing-frame B, intersected by a vertical line passing through the center of shaft *b*, is a spring-actuated tumbler, *m*. The upper arm of this tumbler is struck by the finger *k* once during each revolution as the bed approaches the position shown in said Fig. 1, and the horizontal arm of said tumbler is thereby oscillated from behind a shoulder made in the upper portion of a boss, *K*, fast on the rod *h*. The moment this rod is released, by reason of the tumbler being acted upon by the finger *k*, a coil-expansion spring surrounding the rod *h*, between said boss *K* and frame A, pushes the rod to the right side of the machine, and thus by reason of the bifurcated arm *f* disengages the clutch *F* from the drive-pulley.

In order that the momentum acquired by the shaft *g* when in operation may not affect it when the clutch *F* is withdrawn from engagement with the drive-pulley, I slightly bevel the end edges of said clutch nearest frame A and provide a circular depression in 35 the bearings of the drive-shaft in the contiguous side of the frame A and obversely bevel the inner side walls thereof. When clutch *F* is withdrawn from engagement with the drive-pulley, it enters said depression in the bearings 40 of the shaft, and coming in contact with the beveled surfaces thereof forms a frictional contact, which immediately brakes the shaft.

In order to keep the plate which is to be shaved in the position shown in dotted lines in 50 Fig. 2, I provide the longitudinal ledges *x* and *y*. These ledges may be cast in one piece with the bed; but I prefer to make one—say *x*—divided at its center of length, so that by adjusting bolt *x'* vertically (when the bed is in position shown in Fig. 1) I secure the plate better and make it fit more snugly the curvature of the bed. To accomplish this I secure bolt *x'* to a laterally-projecting arm, *v*, which moves in a recess in the edge of bed, as shown. Passing vertically upward from this arm *v* through the flange of the contiguous edge of bed D is a screw, *t*, which on being turned raises or lowers said bolt *x'*, so as to lock the plate in position or release it therefrom, as desired.

65 In order to trim the edges of the plate as its back or concave surface is being shaved, I journal in lugs *r r*, projecting down from the

circular bearing-frames B, as illustrated, the trimmer-shaft M. This shaft M has a rotary cutter, *n*, which is of such radius and so located with reference to the plate that it trims off the edges projecting beyond the edges of the bed. This shaft M is driven through the medium of a pulley placed on its opposite end, which projects beyond the end of frame A, as 75 shown.

The operation of my invention is simple. The bed being in the position shown in Fig. 1, the plate to be shaved is pushed in from the high end of the machine, so that its side edges 80 rest on the ledges *x y*. Ledge *x* is then so adjusted as to securely hold the plate in position. Lever I is then grasped and oscillated toward the machine, thus throwing the clutch into engagement with the drive-pulley and imparting 85 motion to the rest of machine. When lever I is manipulated so as to throw the clutch into engagement with the drive-pulley, the rod *h* is pulled toward said pulley, and the tumbler *m*, snapping down behind the boss *K*, maintains said rod in such position until the bed has revolved and assumed such position that finger *k* strikes said tumbler, releases said spring-actuated rod, and withdraws the clutch 90 from engagement with the drive-pulley. Thus 95 the bed having completed a revolution and carried the work under the knife in such manner as to shave it, the work is removed and the machine is ready for a fresh supply.

The details of my invention as hereinbefore 100 described need not be strictly adhered to when being constructed, for it is evident that various changes could easily be conceived of by expert workmen which would perform the function of the parts they were substituted for, 105 but would not change the principles which actuated me when constructing. All such modifications I wish to be understood as claiming.

What I claim as new is—

1. In a circular-plate-shaving machine, the 110 combination, with a stationary knife, of a circular bed provided with means for holding the plate and having a revolving motion around said knife.

2. In a circular-plate-shaving machine, the 115 combination, with a circular bed capable of securely holding the plate, of a trimmer or cutter, *n*, and shaft M, so located with reference to said bed that as the latter revolves the edges of the plate projecting beyond the adjacent edges of said bed are trimmed.

3. In a circular-plate-shaving machine, the 120 combination, with a knife, E, of bed D, revolving in suitable bearings, worm-gear F', worm C, pulley e, and clutch F, as and for the 125 purpose set forth.

4. In a circular-plate-shaving machine, the 130 combination, with knife E, knife-frame e, and stationary shaft *b*, secured in the vertex of a Δ frame at one end and its other end resting in the bore of a wheel-frame, *d*, of the bed D and wheel-frame *d*, and means, as described, for operating said bed.

5. In a circular-plate-shaving machine, the

combination, with a stationary knife, of a bed, D, having ledges *x* and *y*, said ledge *x* having arm *v*, which moves in a recess in the adjacent edge of said bed, and screw *t*, as set forth.

5 6. In a circular-plate-shaving machine, the combination, with the bed D, frames B, in which the same revolves, worm-gear F', worm C, shaft *g*, pulley *e*, and clutch F, of bifurcated arm *h* and lever I, as described.

10 7. In a circular-plate-shaving machine, the combination, with bed D, frames B, in which the same revolves, gear F', worm C, shaft *g*,

pulley *e*, and clutch F, engaging therewith, of arm *f*, rod *h*, boss and expansion-spring thereon, tumbler *m*, and finger *k*, secured, respectively, 15 to frame B and the journal-piece of bed D, as and for the purpose set forth.

In testimony that I claim the foregoing as my own I hereunto affix my signature in presence of two witnesses.

GEORGE E. LLOYD.
